UNITED STATES PATENT OFFICE.

CASPER FAUST, OF OSHKOSH, WISCONSIN.

BOLSTER-STAKE HOLDER.

1,139,655.

Specification of Letters Patent. Patented May 18, 1915.

Application filed March 25, 1915. Serial No. 16,980.

To all whom it may concern:

Be it known that I, CASPER FAUST, a citizen of the United States, and resident of Oshkosh, in the county of Winnebago and 5 State of Wisconsin, have invented certain new and useful Improvements in Bolster-Stake Holders; and I do hereby declare that the following is a full, clear, and exact description thereof.

10 My invention refers to releasable bolster stake holders of that general type disclosed in the patent issued to me May 12, 1914, No. 1096028, and has for its object to provide a simple, economical and positive cast-off 15 mechanism for the locking means of a movable member of the bolster socket.

With the above objects in view the invention consists in certain peculiarities of construction and combination of parts as set 20 forth hereinafter with reference to the accompanying drawings and subsequently claimed.

In the drawings Figure 1 represents a general view of one end of a flat car provided 25 with stakes for the support of the load socketed in a holder embodying the features of my invention, the view illustrating a manually controlled runner for operating the cast-off mechanism from a distance outside 30 the field of drop of the load when the stake is released; Fig. 2, an enlarged detailed elevation of the stake-holder with the sill of the car in section, as indicated by line 2—2 of Fig. 1; Fig. 3, a sectional plan view of 35 the same, the section being indicated by line 3—3 of Fig. 2; Fig. 4, another detailed sectional view of the stake-holder socket showing the novel cast-off mechanism, the section being indicated by line 4—4 of Fig. 2; 40 Fig. 5, represents a detailed sectional view of another form of cast-off mechanism; Fig. 6, a detailed face view of the same showing a locking tumbler swung in position to bind the trigger member shown in connection 45 with that form of my device illustrated in Fig. 5; Fig. 7, a sectional plan view of the cast-off mechanism showing a modified form of release elbow link, which may be temporarily attached to a swinging dog member 50 constituting the main element of the lock and release means, and Fig. 8, a face view of still another form of trigger-attaching means.

Referring by characters to the drawings, 55 A represents the side sill of a flat car bottom, to which sill is secured a socket bracket

B having extended cheek-pieces 8 and 8' forming the side walls of said bracket.

The front wall of the socket bracket comprises a removable saddle plate 9 having inwardly extended supporting teeth 9' that articulate with notches 9'' that are formed in ends of the cheek-pieces. The saddle-plate is also provided with end lugs 10, to which are hingedly secured ends of saddle-retaining links 12, 12'. The free looped end of each retaining link is adapted to engage apertured lugs 14, 14', respectively, that project from the outer opposite faces of the cheek-plates. The link 12 and its associated 60 lug 14 are permanently coupled by a spring pin 13, which pin is anchored in the base of the socket bracket and is provided with a nose that engages the pin-receiving aperture of the lug 14, whereby the link 12 is permanently locked and thus forms a shackle connection between the socket-bracket and saddle, which saddle, when bridged between the cheek-plates, completes the socket for the reception of the squared end of a bolster stake 65 A'. It is understood, however, that the socket and bolster stake end may be formed curvilinear in cross-section without departing from the spirit of my invention, such curvilinear form being illustrated in the 70 patent referred to heretofore. The corresponding saddle retaining link 12' is temporarily secured to the lug 14' by a cotter pin 15, which is seated within the lug aperture 75 and is shackled to the socket bracket by a 80 light flexible runner 16 in order that said cotter pin may be retained when not in use, it being understood that this pin is manually released preparatory to a cast-off operation 85 of the stake from a distance.

As shown in Figs. 2 and 4, the cheek-piece 8 is formed with an ear 8'', to which is pivotally connected a swinging dog 17, which dog is formed with a neck-piece 17' having an aperture 17'' in its end. The 90 shank of the neck-piece has projecting therefrom a release nose 17''', between which nose and the short finger, a throat 18 is formed for the reception of a tongue 19 that projects from and constitutes a part of the link 12'. Hence when the link is in its locked position, the tongue is nested within the throat portion of the dog, as best shown 95 in Fig. 4, with the release nose 17''' positioned back of the same. The end portion 100 of the dog neck is adapted to engage the cheek-piece at its lower end and is locked in 105 the latter position by a pin 20.

Referring by characters to the drawings, 110 A represents the side sill of a flat car bottom, to which sill is secured a socket bracket

this position by a trigger 20 having a stem which is guided in a barrel 21 that forms part of the dog neck. Reciprocatative movement of the trigger in one direction is limited by a stop-pin 21' that is carried by the trigger stem and arranged to engage the barrel. The lower end of the stem is arranged to enter an aperture 22, which aperture is formed in a horizontal flange 22' that constitutes part of the cheek-piece, the same being provided with a corresponding flange at its upper end, whereby the cheek-pieces are reinforced from the base of the socket bracket. The stem of the trigger is also provided with a shoulder extension 23', which projects upon either side of the stem proper. The shoulder is engaged by a lever link 23 that is bent in elbow form, the outer stretch of which rests upon the outer edge of the flange 22, while the inner stretch passes through the aperture 17' in the end of the dog nose. In the position just described the cast-off mechanism comprising the dog and its associated parts, is locked to prevent movement of the link 12', even though the retaining cotter-pin 15 should be disengaged from the lug 14'.

In order to prevent inadvertent release of the dog due to vibration of the car, whereby the trigger 20 may shift upwardly from engagement with the socket 22, I provide a trigger-locking tumbler 24. This tumbler is in pivotal connection with the dog and is swung to its locking position and, when so swung, its lower face will engage the upper end of the trigger stem and prevent inadvertent rise of the same.

When it is desired to release the stake A from its socket, the operator removes the cotter-pin 15 and inserts the hooked end 25 of a release runner 26 into the depending free end of the lever link 23. The operator next swings the tumbler clear of the end of the trigger barrel and moves to a position at the end of the runner indicated at α in Fig. 1 of the drawings. A manual pull upon the runner will cause the lever link to initially rise and thus positively lift the trigger 20 from its engagement with the flange socket 22 and after such disengagement it is obvious that a further pull of the runner will cause the dog 17 to swing outwardly. The swinging movement of the dog will cause engagement of the release nose 17'' of the same with the link tongue 19, whereby said link is stripped from the lug 14 and pressure of the load upon the stake will thus cause displacement of the saddle, whereby said stake will swing clear of the socket and permit the load of logs or other articles contained upon the flat car to clear the same.

While I have shown a release runner in the form of a chain stretch, it is obvious that I may, in some instances, utilize a light

rod for the same purpose having a hooked end for engagement with the lever link 23 of the cast-off mechanism.

As shown in Fig. 7, I may also, without departing from the spirit of my invention, employ a lever link 23' having a single stretch that is bent downwardly similar to the link shown in Fig. 4 and the single stretch in this instance may have a right-angle pintle nose 23'', which may be temporarily inserted into the aperture 17' of the dog neck.

Referring to Figs. 5 and 6, the same type of dog 17 is employed, but in connection with this dog, I show a trigger 20' of the bell-crank type, which trigger is pivoted to the end of the neck portion of said dog. One arm is formed with a locking finger 20'' for engagement with the aperture 22, while the opposite arm is formed with an aperture 17' for the insertion of the hooked end of a runner, whereby the dog is released preparatory to swinging outwardly for freeing the tongue portion of the saddle link. The elbow trigger in this instance is locked against movement by a tumbler 24', which is pivoted to the neck of the dog and swung across the path of travel of the release arm of said trigger and when the trigger is to be released, it is obvious that the tumbler is swung to a position in alignment with the dog.

Referring to Fig. 8 of the drawings, I have shown a slid able trigger 27 having an elongated slot therein for engagement with a guide-lug 29, which lug projects from the body of the dog. The guide-lug has projecting nibs 29' which are upset upon washers 30, whereby the trigger is confined. This construction is, in some instances, preferably, due to the fact that the parts can be economically assembled and cast, dispensing with cores or the like which would be necessary wherein the sleeve 21 is utilized as a retainer for the trigger, such as shown in Figs. 2 to 4 inclusive.

I claim:

1. In a bolster stake holder having a bracket provided with cheek-pieces, a saddle adapted to bridge the cheek-pieces in swinging union with one of the same, a lug carried by the opposite cheek-piece, and a link connected to the saddle engageable with the lug; the combination of a cast-off mechanism for the link comprising a depending dog in swinging union with the associated cheek-piece adapted to nest over the end of said link, a trigger carried by the dog and engageable with the cheek-piece, and a manually controlled pull runner for releasing the trigger from its cheek engagement.

2. In a bolster stake holder having a bracket provided with cheek-pieces, a saddle adapted to bridge the cheek-pieces in swinging union with one of the same, a lug car-

ried by the opposite cheek-piece, and a link connected to the saddle engageable with the lug; the combination of a cast-off mechanism for the link comprising a depending dog in swinging union with the associated cheek-piece adapted to nest over the end of said link, a trigger carried by the dog and engageable with the cheek-piece, a manually controlled pull runner for releasing the trigger from its cheek engagement, and a manually controlled locking templet carried by said dog for engagement with the trigger, whereby the latter is held against movement.

3. In a bolster stake holder having a bracket provided with cheek-pieces, a saddle adapted to bridge the cheek-pieces in swinging union with one of the same, a lug carried by the opposite cheek-piece, and a link connected to the saddle engageable with the lug; the combination of a cast-off mechanism for the link comprising a depending dog in swinging union with the associated cheek-piece adapted to nest over the end of said link, a trigger carried by the dog and engageable with the cheek-piece, a lever-link fulcrumed to the dog, means extending from the trigger for engagement with the lever-link, and a manually controlled runner adapted to be connected to said link for operating the cast-off mechanism.

4. In a bolster stake holder having a bracket provided with cheek-pieces, a saddle adapted to bridge the cheek-pieces in swinging union with one of the same, a lug carried by the opposite cheek-piece, and a link connected to the saddle engageable with the lug; the combination of a cast-off mecha-

nism for the link comprising a depending dog in swinging union with the associated cheek-piece adapted to nest over the end of 40 said link, a trigger in slidable union with the dog adapted to engage the cheek-piece, whereby said dog is locked, an elbow link in pivotal union with said dog, a shoulder projecting from the trigger for engagement 45 with the elbow link, and means for exerting pull upon the link at a distance, whereby the cast-off mechanism is operated.

5. In a bolster stake holder having a bracket provided with cheek-pieces, a saddle 50 adapted to bridge the cheek-pieces in swinging union with one of the same, a lug carried by the opposite cheek-piece, and a link connected to the saddle engageable with the lug; the combination of a cast-off mechanism for the link comprising a dog in pivotal union with the lug-carrying cheek-piece, the 55 dog being provided with a depending neck and short nose portion forming a throat therebetween, a tongue extending from the 60 link adapted to nest within the throat, a trigger carried by the dog and engageable with the cheek-piece, and a manually controlled pull runner for releasing the trigger from its cheek engagement. 65

In testimony that I claim the foregoing I have hereunto set my hand, at Milwaukee, in the county of Milwaukee and State of Wisconsin, in the presence of two witnesses.

CASPER FAUST.
